UNITED STATES PATENT OFFICE

2,666,571

COMPRESSOR

Marcel René Armand Chabay, Paris, France, assignor to Societe d'Inventions Aeronautiques et Mecaniques S. I. A. M., Geneva, Switzerland, a corporation of Switzerland

Application July 22, 1948, Serial No. 40,031

Claims priority, application France July 28, 1947

2 Claims. (Cl. 230—182)

1

The present invention relates to improvement in multiple stage piston compressors, and is characterised in particular by the fact that the various cylinders, and also the accumulation chambers or reservoirs for the gas compressed in the cylinders other than the high pressure cylinder, are provided in a single cylinder block provided with cooling fins suitably arranged at its periphery.

An extremely strong and compact multi-stage compressor is thus obtained. The arrangement of the reservoirs, which are used for storing the air compressed in the low and intermediate pressure cylinders in the cylinder block itself, eliminates the pipes which connected said cylinders to the various reservoirs and thereby avoids the leaks which occurred at the joints of such pipes.

The invention also covers other characteristic arrangements which may be used separately or in any combinations, in particular:

1. The accumulation chambers or reservoirs for the gas compressed in the low and intermediate pressure cylinders are located in the cylinder block at the periphery thereof and near the base of the cylinders so that the walls of said chambers are perfectly cooled and are not subjected to the rise of temperature caused by the compression of the gas in said cylinders.

2. The passages connecting said accumulation reservoirs or chambers to the various cylinders are provided in the walls of the cylinder block and of the cylinder head of the compressor.

3. The suction and delivery valves of the various cylinders are mounted in easily removable valve-boxes which are fixed either to the cylinder block itself, or to the cylinder head of the compressor, so as to be readily accessible.

4. In order to reduce the size of the compressor as much as possible and decrease the number of cranks on the single crankshaft of this compressor, two or more stages of compression are obtained by means of differential pistons which are adapted to move in coaxial cylinders of suitable diameters.

5. In order to obtain a maximum balance of the work on the crankshaft at each revolution of same, the compression strokes of the pistons are suitably distributed over each revolution of said crankshaft.

6. In the particular case of a three-stage compressor, the compression stroke in the low-pressure cylinder takes place during the suction strokes in the high and intermediate pressure cylinders, and conversely the compression strokes

2

in these latter cylinders take place during the suction stroke in the low-pressure cylinder.

7. The volume of the various accumulation reservoirs or chambers for the gas compressed in the low and intermediate pressure cylinders is a high multiple of the volume of the respective cylinder capacities filled from said chambers in order to prevent the gas from expanding in said chambers when the corresponding cylinders are being filled.

8. The crankcase of the compressor, in which the bearings for the crankshaft are provided, is integral with the cylinder block.

9. The cylinders of the compressor are provided with liners which are forced into suitable bores in the cylinder block and held axially in position by flanges, on the upper face of which is pressed the readily removable cylinder head of the compressor.

10. The cooling of the cylinder block and of the cylinder head, which are both provided with suitable fins, may be effected by a forced air circulation inside a suitable hood surrounding these members.

11. This circulation of cooling air may be produced: by a fan, by an air-blast supplied with compressed air obtained from the delivery of the compressor, by a suitably orientated air inlet arranged in the direction of the relative wind when said compressor is mounted on a vehicle, or by a combination of these means.

The invention will be more clearly understood by means of the ensuing description, made with reference to the accompanying drawing which is only given by way of example and in which:

Fig. 1 is a longitudinal section of the compressor taken along the line I—I of Fig. 2, the pistons being assumed to be near the end of their compression stroke for the low-pressure piston and near the end of their suction stroke for the intermediate and high pressure pistons.

Fig. 2 is a transverse section taken along the line II—II of Fig. 1.

Fig. 3 is a transverse section taken along the line III—III of Fig. 1.

Fig. 4 is a horizontal section taken through the line IV—IV of Fig. 1.

Fig. 5 is a horizontal section taken through the line V—V of Figs. 1, 2 and 3, showing more especially the low and intermediate pressure accumulation chambers, the openings of the passages leading to the upper part of said chambers being shown in dot-and-dash lines, while the pistons are assumed to have been removed.

Fig. 6 is a fragmentary view of an embodiment

of a compressor with a forced circulation of the cooling air.

Fig. 7 is a fragmentary section on a larger scale taken through the line VII—VII of Fig. 6.

Fig. 8 is a transverse section of the cowling taken along the line VIII—VIII of Figs. 6 and 7.

The three-stage compressor, which is illustrated by way of example in the drawings, comprises a cylinder block 1 in which are provided two bores with parallel axes. The bore 2 of smaller diameter is provided with a cylindrical liner 3 which is forced into it and which forms the wall of the high-pressure cylinder 4. The bore 4a is provided with a liner 4b which is forced into it and which is internally bored in such a manner as to form two superposed cylinders of different diameters 5 and 6 which respectively determine the low and intermediate pressure cylinders 5a and 7, as will be explained hereinafter (see in particular Figs. 1 and 3).

The cylinder block 1 is provided, over its entire periphery, with cooling fins 26 which are suitably arranged and calculated to effect a good heat exchange between the cylinder block 1 and the surrounding air. Said cylinder block 1 may, for example, be made of an aluminum alloy, the liners 3 and 4b forming the walls of the various cylinders being of cast-iron or of steel so as to offer great resistance to wear.

The cylinder block 1 is extended at its lower part by a crankcase 8 containing cylindrical bearings 9 and 10, the axis of which is at right angles to the axes of the cylinders and is contained in the same plane. Said bearings 9 and 10 are provided with bushings 11 and 12 in which is journalled the crankshaft 13 of the compressor. Said shaft 13 is provided with two crank-pins 14 and 15 which are set at 180° to one another and are respectively located opposite the high-pressure cylinder on the one hand, and the intermediate and low pressure cylinders on the other hand.

On the crank-pin 14 is journalled an eccentric collar 16 provided with an arm 17 which is pivoted on a pin 18 mounted in the forked end of a cylindrical piston 19 inserted with a running fit in the bore of the liner 3 which forms the high-pressure cylinder. Said piston 19 is provided with a number of circular grooves 20 intended to facilitate the lubrication of the contacting surfaces. It is obvious that said piston 19 could also be provided with fluid-tight devices such as piston-rings.

On the crank-pin 15 of the crankshaft is journalled the bottom end of a connecting rod 22, the top end of which is pivoted on a pin 21 mounted in bearings provided on the skirt of a differential piston. Said differential piston has two superposed skirts 23 and 24 of different diameters respectively corresponding to the diameters of the bores 5 and 6 provided in the liner 4b. Circular grooves 25, which may house fluid-tight devices such as piston-rings, are provided at the periphery of the skirts 23 and 24 of the differential piston. As hereinbefore mentioned, the low-pressure cylinder 5 is formed by the upper end of the bore 5a of the liner 4b, whereas the intermediate-pressure cylinder 7 is formed by the annular space between the surface of the bore 5 of the liner 4b and the skirt 24 of the differential piston.

According to an important feature of the present invention and in order to obtain as uniform a distribution as possible of the mechanical energy over the crankshaft 13 during the rotation thereof, the setting of the crank-pins 14 and 15 and the arrangement of the cylinders and the pistons

have been so provided that the compression stroke in the low-pressure cylinder 5a takes place during the suction stroke in the intermediate and high pressure cylinders, while the compression stroke in these latter cylinders takes place at the same time as the suction stroke in the low-pressure cylinder 5. Furthermore, the useful volumes of the low, intermediate and high pressure cylinders have preferably been chosen so as to correspond to the same initial volume of gas sucked in, taking into account the pressures obtained in these various cylinders at the end of the compression stroke.

One of the ends of the crankshaft 13 of the compressor is adapted to receive a suitable coupling device (not shown) connecting said crankshaft to the driving shaft. Thus the end of said crankshaft may be bored and provided with internal longitudinal splines 27 (Fig. 1).

In order to enable the various members of the compressor to be mounted and removed easily, the lower part of the crankcase 8 is provided with openings 28 which are closed by covers 29 held in position by any suitable means such as screws, studs or the like (not shown).

On the trued upper face of the cylinder block 1 is fixed, by means of screws or studs 30 for example, a cylinder head 31 which is also provided with cooling fins 32. According to a characteristic arrangement of the present invention, the delivery and suction valves of the high and low pressure cylinders, and which will now be described in greater detail, are mounted in said cylinder head 31.

Opposite the upper end of the low-pressure cylinder (see Fig. 1), the cylinder head 31 is provided with a cylindrical opening 33, in the lower part of which is screwed a bushing 34 forming a seat for the suction valve 35 of the low-pressure cylinder 5a. Said bushing 34 is provided with a coaxial inner sleeve 36 which acts as a guide for the stem 37 of the valve 35 and which is connected to the bushing 34 by fins or ribs 38. A suitably calibrated spring 39 which is coaxial to the stem 37 bears, on the one hand against the upper end of the sleeve 36, and on the other hand against a washer 37a fixed on the stem 37 of the valve 35 so as normally to hold said valve against its seat. In the screw-threaded upper portion of the opening 33 is screwed either an air inlet sleeve 39a provided with one or more filters as shown, or a pipe connected to the delivery end of a supercharger or like machine in the case in which the improved three-stage compressor according to the invention operates with a forced feed.

Opposite the upper end of the low-pressure cylinder 5 and diametrically opposite the opening 33, the cylinder head 31 has on its lower face a blind opening which leads to a chamber 42 provided in said cylinder head 31. In the screw-threaded lower end of said opening is screwed a bushing 43 forming a seat for the delivery valve 44 of the low-pressure cylinder 5a. Said valve 44 is normally held against its seat by means of a suitably calibrated spring 45 which is adapted to bear, on the one hand against the bottom of a blind hole provided in the stem of said valve, and on the other hand against the bottom of a blind bushing 47 which is centred and held in position in the chamber 42 by means of ribs 48. Said chamber 42, which is crescent-shaped (see Fig. 4) is connected, through a conduit 49 provided in the cylinder head 31, to a conduit 51 (Fig. 5) which in principle is parallel to the axes of the cylinders. Said conduit 51 opens at its lower end

into a chamber 52 (Fig. 3) provided in the lower part of the cylinder block for reasons which will be explained hereinafter. Said chamber 52 (see Figs. 1, 3 and 5) is connected through a passage 53 to a radial hole 54 provided in the wall of the cylinder block 1 opposite the liner of the intermediate-pressure cylinder. In said hole 54 is mounted a valve-box 56 which can be easily removed by means of a blind cylindrical nut 55. Said valve-box 56 contains a valve 57 which forms the inlet valve of the intermediate-pressure cylinder 7 and which is normally held against its seat by a suitably calibrated spring 58a. When the valve 57 is lifted off its seat, it thus places the chamber 52, called low-pressure chamber, in communication with the inside of the intermediate-pressure cylinder 7 through an opening 58 provided in the liner 4b opposite the valve 57.

In the liner 4b and opposite the opening 58 is provided an opening 59 which opens opposite the seat of a valve-box 60 which is mounted in such a manner as to be readily removable by means of a screw 61, in a radial hole 62 provided in the cylinder block 1. Said valve-box 60 contains a valve 63, called intermediate-pressure delivery valve, which is normally held against its seat by a suitably calibrated spring 64. The inside of the valve-box 60 is connected to a passage 65 which opens into a chamber 66 called intermediate-pressure chamber provided in the lower part of the cylinder block 1 (see Figs. 3 and 4). Said intermediate-pressure chamber 66 is connected, through a passage 67 provided in the cylinder block 1 parallel to the axes of the cylinders, to a passage 68 provided in the cylinder head 31 of the compressor.

Said cylinder head 31 is provided, opposite the upper end of the high-pressure cylinder, with a recess 69 in which is mounted a valve-box 70 held in position by a blind nut 71 which screws on its screw-threaded upper end. The valve-box 70 is provided with two holes 72 and 73, the axes of which are parallel to the axis of the high-pressure cylinder 4. The hole 72 is connected through a radial hole 75 (see Fig. 2) to the passage 68 provided in the cylinder head 31. The lower part of the chamber 72 is chamfered so as to form a seat for the intake valve 76, the stem 77 of which is suitably guided. Said valve 76 is normally pressed against its seat by a spring 78 which is adapted to bear, on the one hand against the valve-box, and on the other hand against a washer 79 fixed on the stem 77 of said valve.

The second hole 73 of the valve-box is terminated by a conical bearing surface forming a seat for a delivery valve 84 which is held against this seat by a spring 82 which is housed in a blind axial cavity of said valve and is adapted to bear against the bottom of a blind guide bush 83. The chamber 73 is connected, through a radial hole 85 provided in the wall of the valve-box 70, to a delivery nozzle 36 provided on the cylinder head 31.

It will be seen that the location and the method of mounting used according to the invention for the intake and delivery valves of the various cylinders of the compressor, enable these various valves to be adjusted and removed easily.

According to a feature of the invention and as hereinbefore described, it can be seen that the accumulation chambers or reservoirs 52 and 66 for the gaseous fluid compressed in the low and intermediate pressure cylinders are provided in the cylinder block 1 itself and at the part of same corresponding to the base of the cylinders,

i. e. at the point where the temperature is lowest since the heat produced by the compression of the gaseous fluid in said cylinders is evacuated in principle at the upper part of said cylinders. Furthermore, said accumulation chambers or reservoirs 52 and 66 are perfectly cooled by the fins 28 provided on the cylinder block 1.

The operation of the three-stage compressor hereinbefore described is easy to understand and will now be described. The crankshaft 43 and the various pistons being assumed to occupy the positions shown in the drawing; when said crank-shaft rotates, the low and intermediate pressure differential piston moves downwards and a certain vacuum is created in the upper part of the low-pressure cylinder 5a. The valve 35 lifts off its seat and the gaseous fluid penetrates into the cylinder 5a throughout the whole of the suction stroke of the low-pressure piston, through the filter or filters 49 and the sleeve 39a. At the end of this suction stroke, the valve 35 is closed by the action of the spring 39. When the differential piston moves upwards, the gas sucked into the cylinder 5 is compressed and when its pressure exceeds that corresponding to the calibration of the spring 45 of the low-pressure delivery valve 44, said valve 44 lifts and the gas compressed at low pressure in the cylinder 5a is forced through the chamber 42 and the passages 49 and 51 into the low-pressure accumulation chamber or reservoir 52 where it is cooled by the contact of the cold walls of said chamber.

During the up-stroke of the differential piston corresponding to the compression stroke in the low-pressure cylinder 5a, a vacuum is created in the intermediate-pressure cylinder 7, the intermediate-pressure inlet valve 57 is lifted off its seat against the action of the calibrated spring 58a and the gas which is compressed at low pressure and stored in the chamber 52 penetrates into the intermediate-pressure cylinder 7. When the differential piston reaches its extreme high position, the intermediate-pressure inlet valve 57 closes. When said differential piston moves downwards (suction stroke in the low-pressure cylinder) the low-pressure gas contained in the intermediate-pressure cylinder 7 is compressed and when its pressure exceeds that corresponding to the calibration of the spring 64 of the intermediate-pressure delivery valve 63, said valve 63 is lifted off its seat and the gas compressed at intermediate-pressure in the cylinder 7 is forced through the opening 59, the valve-box 60 and the passage 65 into the intermediate-pressure accumulation chamber or reservoir 66 where it is cooled by contact with the cold walls of said chamber.

At the beginning of the down-stroke of the high-pressure piston 19, which takes place when the differential piston moves upwards (compression stroke in the low-pressure cylinder and suction stroke in the intermediate-pressure cylinder), the high-pressure inlet valve 70 is lifted off its seat and the compressed gas at intermediate pressure contained in the intermediate-pressure chamber 66 penetrates into the cylinder 4 through the passages 67 and 68; the opening 75, the chamber 72 and the opening uncovered by the valve 76. At the end of the suction stroke of the high-pressure piston 19, the valve 76 is closed by the action of the calibrated spring 78. When the piston 19 moves upwards, the gas at intermediate pressure contained in the cylinder 4 is compressed and when its pressure exceeds that corresponding to the calibration of the spring 82 of the high-pressure delivery valve

81, said valve 81 lifts and the gas compressed at high pressure in the cylinder 4 is forced through the chamber 73 into the delivery nozzle 86 of the compressor.

According to the invention and in order to prevent the pressure of the gas contained respectively in the low and intermediate pressure accumulation chambers or reservoirs 52 and 66 from falling considerably during the filling of the intermediate-pressure and high-pressure cylinders 7 and 4, the volume of said accumulation chambers or reservoirs is chosen equal to a high multiple of the respective cylinders to be filled.

According to the invention, the lubrication of the various members is forced. The lubricant is forced through a pipe (not shown) into a chamber provided in the crankcase wherein said lubricant is conveyed in the known manner and through suitable ducts 28 either directly to various members to be lubricated (bearings, connecting-rod big end, eccentric), or by projection on to certain other members (cylinders, pistons, connecting-rod small end, etc.).

In order to provide a more efficient cooling of the cylinder block 1, a forced air circulation may be produced on the fins 26 of the cylinder block 1 and also on the fins 32 of the cylinder head 31. For this purpose, and in an embodiment which appears to be advantageous at the present moment, a cowling 89 of sheet metal for example, is arranged round the compressor, as is best shown in Figs. 6 to 8 of the drawings. Said cowling 89 is eccentric with respect to the cylinder block 1 in such a manner that at one point it is tangential to the periphery of the fins 26 and to a transverse fin 26a. The cooling air is admitted under said cowling on one side of this tangential portion, on to the fins. The outlet of the air is effected on the opposite side to its inlet, through an opening 90 provided in the cowling 89 in such a manner that said air is constrained to flow over the entire surface of the fins 26 and 32 of the cylinder block and head 1 and 31 respectively, thereby effecting a perfect cooling of the compressor.

The cooling air may be forced for example by a centrifugal fan 91 mounted on the end of the crankshaft 13 of the compressor. A suitable case 92, integral with the cowling 89 of the compressor and surrounding the blades 91 of the fan, conveys the air forced in to the suitable point of the cowling 89 as hereinbefore mentioned. Instead of using a fan, it would also be possible, when the compressor is mounted on a vehicle, to arrange an air intake in the direction of the relative wind and thereby obtain a flow of cooling air inside the cowling 89. It is also possible, as shown in Fig. 7 of the drawings, to combine both of these means, the fan being supplied with the air conveyed through a pipe 92 leading to the intake located in the relative wind. The opening of the supply pipe 93 of the low-pressure cylinder of the compressor may be located inside said pipe 92 so as to provide a slight supercharging of said compressor.

It is obvious that the invention is not limited to the embodiments hereinbefore described and illustrated by way of example, but extends to all embodiments involving the use of the features hereinbefore set forth and fulfilling the desired

requirements. Thus, in particular, the compressor according to the invention could be a two-stage compressor by eliminating either the high-pressure cylinder and piston, or the intermediate-pressure cylinder and piston and their associated members, or again, said compressor could be a four-stage compressor by replacing the high-pressure cylinder and piston by a double cylinder and a differential piston of the type of those hereinbefore described by the name of low and intermediate pressure cylinders and pistons. Instead of being parallel to one another, the axes of the cylinders could be inclined (V-type arrangement) or be in alignment (so-called flat type).

I claim:

1. A three stage piston type compressor comprising a single cylinder block with two bores therein, said bores having parallel axes, a first piston slideable in one bore, which constitutes the high pressure cylinder of said compressor, a differential piston having mounted thereon two superposed skirts of different diameters, the top skirt being of a larger diameter than the bottom skirt, and slideable in the other bore having therein a liner with stepped diameters to receive said skirts, the portion of the bore above the top skirt constituting the low pressure cylinder of the compressor and the portion of the bore between the outer surface of the lower skirt and the inner surface of the liner having a diameter sufficient to receive the top skirt constituting the intermediate pressure cylinder, a single driven crankshaft and means connecting each of said pistons to said crankshaft whereby the compression stroke in the low pressure cylinder takes place during the suction stroke in the intermediate and high pressure cylinders, while the compression stroke in these latter cylinders takes place at the same time as the suction stroke in the low pressure cylinder.

2. A compressor according to claim 1, comprising inside of said cylinder-block, near its periphery and in the vicinity of the lower part of said bores, around said bores, two accumulation, passage and cooling chambers for the compressed gas, the one, for low pressure, receiving the compressed gas coming from the low pressure cylinder and feeding the intermediate pressure cylinder, the other, for the intermediate pressure, receiving the compressed gas coming from the intermediate pressure cylinder and feeding the high pressure cylinder.

MARCEL RENÉ ARMAND CHABAY.
